UNITED STATES PATENT OFFICE.

WILLIAM P. STROKE, OF BUFFALO, NEW YORK

DESIGN FOR A RACK FOR SUPPORTING WATCHES, WATCH-CHAINS, KEY-RINGS, AND
SIMILAR ARTICLES.

47,123.

Specification for Design.

Patented Mar. 16, 1915.

Application filed January 8, 1915. Serial No. 1,250. Term of patent 7 years.

To all whom it may concern:

Be it known that I, WILLIAM P. STROKE, a citizen of the United States, residing at Buffalo, in the county of Erie and State of New York, have invented a new, original, and ornamental Design for Racks for Supporting Watches, Watch-Chains, Key-Rings, and Similar Articles, of which the following is a specification, reference being had to the accompanying drawing, forming part thereof.

The figure is a perspective view of the

racks for supporting watches, watch chains, key rings and similar articles, showing my new design.

I claim:

The ornamental design for a rack for supporting watches, watch chains, key rings, and similar articles, as shown.

WM. P. STROKE.

Witnesses:

CHARLES A. KLOCKE,
CHARLES J. STROKE.
